UNITED STATES PATENT OFFICE.

LUCIAN W. BUGBEE, OF SOUTHBRIDGE, MASSACHUSETTS, ASSIGNOR TO AMERICAN OPTICAL COMPANY, OF SOUTHBRIDGE, MASSACHUSETTS, A CORPORATION OF MASSACHUSETTS.

DESIGN FOR AN INSTRUMENT FOR DETECTING INTERNAL STRAINS IN LENSES.

41,835.

Specification for Design.

Patented Oct. 10, 1911.

Application filed June 29, 1911. Serial No. 636,131. Term of patent 7 years.

To all whom it may concern:

Be it known that I, LUCIAN W. BUGBEE, a citizen of the United States, residing at Southbridge, county of Worcester, State of Massachusetts, have invented a new, original, and ornamental Design for an Instrument for Detecting Internal Strains in Lenses, as herein set forth, reference being had to the accompanying drawings, forming a part thereof.

In the accompanying drawings; Figures

I and II are perspective views of the same instrument taken from opposite sides.

I claim:

The ornamental design of an instrument for detecting internal strains in lenses as shown.

LUCIAN W. BUGBEE.
